Inventor:

Chas. W. Smith

UNITED STATES PATENT OFFICE.

CHARLES W. SMITH, OF EVANS, NEW YORK.

IMPROVED WASHING-MACHINE.

Specification forming part of Letters Patent No. **36,307**, dated August 26, 1862.

To all whom it may concern:

Be it known that I, CHARLES W. SMITH, of Evans, New York, have invented certain Improvements in the Construction of Washing-Machines; and I do hereby declare that the following is a full description of the said invention, reference being made to the drawings, making part of this specification, and to the letters marked thereon.

A represents a wash-tub of the ordinary form, one side being partially removed to show the dasher.

B is a cross-bar slipping into the handles of the tub, supporting the standard C, which serves as a fulcrum for the lever D, and perforated to admit the action of the connection-rod E, by which the dash F is pressed upon the clothes confined within the netting G.

The tub being partially filled with water,

and the fabric to be cleansed being placed within the netting, as above indicated, the lever D is actuated, and by this means the clothes are compelled rapidly to absorb and discharge the water. In this manner they are cleansed without rubbing, and therefore without injury to the most delicate fabric.

Having thus described my invention, what I claim as new therein, and desire to secure by Letters Patent, is—

The combination of the dasher F, the bar B, the standards C E, and the lever D, arranged to be used in connection with an ordinary wash-tub, substantially as described.

CHAS. W. SMITH.
